2 SHEETS—SHEET 2.

UNITED STATES PATENT OFFICE.

ANTHONY G. KAISER, JACOB NAHIRNY, AND CHARLES F. ERXLEBEN, OF ST. LOUIS, MISSOURI, ASSIGNORS OF ONE-FOURTH TO THE MEDART COMPANY, OF ST. LOUIS, MISSOURI.

SAFETY CUPOLA TAPPER AND STOPPER.

Application filed June 6, 1922. Serial No. 566,833.

To all whom it may concern:

Be it known that we, ANTHONY G. KAISER, JACOB NAHIRNY, and CHARLES F. ERXLEBEN, citizens of the United States, Poland, and the United States, respectively, and residents of St. Louis and State of Missouri, have invented certain new and useful Improvements in Safety Cupola Tappers and Stoppers, of which the following is a specification.

10 This invention relates to an improved device for opening and closing the tap hole of a cupola furnace.

It is general practice at the present time to employ a pole about ten feet long with a wet fire clay butt on the end thereof which is forced into the tap hole when it is desired to stop the flow of molten metal.

This is open to many objections and is the frequent cause of accidents. It requires 20 skilled labor and where the foundries run a continuous heat, the cupola man must be frequently relieved.

The object of our invention is to provide a device for stopping and tapping the tap 25 hole of a cupola or similar furnace that will be simple and efficient and can be operated by any employee after short instruction without danger to any of the workmen.

Another object is to provide such a device 30 that will be especially useful in furnaces having a continuous flow as it enables the elimination of the usual double spout.

A further object is to provide a device that can be adjustable so that it will exactly 35 fit the tap hole, and can also be moved out of the way for repairs to the spout or when it is desired to substitute a new stopper.

Other objects will be apparent from the following detailed description and the appended claims.

In the drawings:

Figure 1 is a side elevation of the device with the furnace wall in section.

Figure 2 is a top plan view of a portion 45 of the device.

Figure 3 is an end view of the device.

Figure 4 is a sectional view of the stopper.

The cupola wall 1 is of the usual construction and is provided with a tap hole 2 through which the molten metal flows into a trough 3 having any suitable lining 4. On one side of the trough are fastened brackets 5 and 6 terminating at their upper ends in

ears in which is mounted a rod 7 which may be held by screws 8 or other similar fastenings which permit free turning movement of the rod 7. Collars 9 and 10 are mounted on the rod 7 and held by fastenings 11 in positions where they abut the brackets 5 and 6 respectively. In these collars are mounted rods 12 and 13 that extend across the trough 3 above the edges thereof. These rods are held in the collars by set screws 14 or similar fastenings.

On the rods 12 and 13, over the middle of the trough when in operative position, is mounted a casting 15 held in adjusted position by a set screw 16 engaging the rod 13 and a similar set screw 17 engaging the rod 12. By means of these set screws the casting 15 may be adjusted laterally of the trough. A second casting 18 has downwardly extending ears 19 at the outer end which fit on each side of the upper portion 75 of the casting 15. Registering openings are provided in the ears 19 and the casting 15 and a shaft 20 fits therein. A set screw 21 fastens the shaft 20 and casting 15 together allowing the casting 18 to rotate about the 80 shaft 20 as a pivot.

The body of the casting 18 is formed as a hollow cylinder 22 and in said cylinder is adapted to slide a plunger 23 into one end of which is fastened a rod 24 carrying the 85 stopper 25 at its other end. The front end of the plunger 23 is provided with ears 26 between which fits the end of a link 27 which is held by a pivot pin 28 passing through the ears 26 and link 27. The front 90 end of the link 27 is detachably pivoted in any suitable manner at 28 to a lever 29 the end of which is pivoted at 30 to an upward extension 31 of the collar 10.

The under side of the cylindrical member 22 rests against an adjustable set screw 32 screwed into the casting 15, and this screw limits the downward movement of the cylinder and the plunger 23 carried thereby, and may be adjusted so that the stopper 25 will 100 be exactly aligned with the tap opening 2. The casting 15 is also provided with a cam surface 33, best shown in Figure 1, and the plunger 23 carries in a depression in its under surface a roller 34 which is adapted to 105 ride up the surface 33 as the plunger is withdrawn, thereby moving the parts from the full line position in Figure 1 to the dot-

and-dash line position so that the stopper 25 may be lifted out of line with the tap hole 2, thereby avoiding any interference of the parts with the flow of metal from the 5 opening.

A steel cable 36 is fastened at one end to the lever 29 at 37 and passes over a pulley 38 carried in a bracket 39 fixed to the side of the trough 3. At its other end the cable 10 carries a weight 40. Obviously when the handle 29 is released, the weight 40 will return the parts to operative position, the screw 32 determining the limit of downward movement of the parts.

15 Referring particularly to Figure 4, the stopper or butt 25 is shown as being preferably constructed in the following manner. A steel nut 41 is screwed on the end of the rod 24 and has a covering of fire-clay 42. The body 43 of the stopper is 20 formed of suitable ingredients, such as those used in the manufacture of crucibles. The body is held in position by a screw bolt 44 that passes therethrough and screws 25 into the nut 41. The bolt is countersunk in the body and the depression is filled with fire clay 45 to protect the bolt from heat.

The breast 46 of the cupola 1 surrounding the tap hole is formed of fire clay, river sand 30 and ground fire clay brick mixed with molasses water. While it is still in a soft state the butt of stopper 25 is pressed into it, forming a depression surrounding the tap hole which will exactly match the stopper.

35 This provides for a perfect fit between the two engaging parts, and also provides a greater surface of engagement than is usually the case.

It is to be noted that through the set 40 screws 16 and 17 the device may be adjusted laterally as a whole over the trough, while a variation of the set screw 32 will determine the normal vertical position of the plunger. By these adjustments the stopper will be positioned so that it automatically returns to 45 perfect working position upon a release of the handle 29.

The whole device may be swung to one side about the shaft 7 when repairs are necessary. If the new stopper is needed the 50 nut 41 may be unscrewed from the rod 24, or the rod 24 may be unscrewed from the plunger member 23. Furthermore, by a detachment of the pin 28 the whole plunger 55 may be quickly removed. It is obvious therefore that a new stopper may be quickly substituted for an old one without any delay in the operation of the device.

60 However, a stopper constructed in the manner described will have a long life and require replacement infrequently. It is obvious that certain features of the invention may be used without others, and that minor changes may be made in form and proportion 65 without departing in any way from the

spirit of the invention. It is to be understood that the invention is to be regarded as limited only by the scope of the appended claims.

We claim as our invention.

1. A tapping apparatus for furnaces having the usual taphole and trough leading therefrom, comprising a frame rotatably mounted on the side of the trough to turn about a longitudinal axis, a guide carried by 70 said frame, a plunger slideable in said guide, a stopper connected to said plunger and adapted to close the tap hole, and means for operating said plunger.

10 2. A tapping apparatus for furnaces having the usual tap hole and trough leading therefrom, comprising a frame carried by the trough, a guide carried by the frame, a plunger slideable in said guide, a stopper connected to said plunger and adapted to 75 close the tap hole, manual means for moving said plunger to open the hole, and means for automatically moving the plunger to close the hole.

80 3. A tapping apparatus for furnaces having the usual tap hole and trough leading therefrom, comprising a frame mounted on the side of the trough, a guide adjustably mounted on said frame, a plunger slideable in said guide, means carried by said plunger 90 to close the tap hole, a lever connected to said plunger to move the same, and means tending to move the lever to position to cause said means to close the tap hole.

95 4. A tapping device for furnaces having the usual tap hole and trough leading therefrom, comprising a frame rotatably mounted on the side of the trough, a guide adjustably and rotatably mounted on said frame, adjustable means for determining the normal position of the guide, a plunger slideable in said guide, a stopper carried by said plunger, and means for operating said plunger.

100 5. A tapping device for furnaces having the usual tap hole and trough leading therefrom, comprising a frame rotatably mounted on the trough, a guide adjustably and rotatably mounted on said frame, a plunger slideable in said guide, a lever for moving the 115 plunger in one direction and automatic means for moving the plunger in the opposite direction.

110 6. A tapping device for furnaces having the usual tap hole, comprising a support, a guide rotatably mounted on said support, a plunger slideable in said guide in substantial alignment with said tap hole, means for withdrawing the plunger, and means for elevating it as it is withdrawn.

115 120 7. A tapping device for furnaces having the usual tap hole comprising a support, a guide rotatably mounted on said support, means for determining the normal position of said guide, a plunger slideable in said 130

guide in substantial alignment with the tap hole, means for withdrawing the plunger, and means for rotating the guide as the plunger is withdrawn.

5 8. A tapping device for furnaces having the usual tap hole, comprising a support, a guide adjustably and rotatably mounted on the support, means for limiting the rotary movement of the guide in one direction, 10 means for closing the tap hole slidably in said guide, and means for controlling said slidable means.

9. A tapping device for furnaces having the usual tap hole, comprising a support, 15 guiding means adjustably and rotatably mounted on said support, stopper carrying means positioned by the guiding means, and means for operating the stopper carrying means.

20 10. A stopper for furnace tap holes comprising a supporting rod, a metal nut

threaded thereon, a fireclay coating for said nut, a composition body, a threaded bolt for attaching the body to the nut, the head of which is countersunk in the body, and a 25 fireclay filling for the countersink.

11. A stopper for furnace tap holes comprising a supporting rod, a metal nut carried thereby, a composition body, a threaded bolt for attaching the body to the nut, and 30 refractory coatings for the nut and head of the bolt.

12. A stopper for furnace tap holes comprising a supporting rod, a metal nut carried thereby, a composition body, means for 35 attaching the body to the nut, and a refractory coating for exposed metal parts.

In testimony whereof, we have hereunto subscribed our names.

ANTHONY G. KAISER.

JACOB NAHIRNY.

CHARLES F. ERXLEBEN.
